UNITED STATES PATENT OFFICE

2,157,449

INSECT EXTERMINATOR

Max Berg, Tulsa, Okla.

Application July 9, 1938, Serial No. 218,457

2 Claims. (Cl. 43—131)

This invention relates to improvements in insect exterminators, and more particularly to a novel coating composition which may be applied to a cardboard card or the like.

One of the objects of the invention is to provide an insect exterminator for cockroaches and other insects which do not have lungs.

A further object is to supply a simple and efficient means for the administration of poison to 10 such insects.

Another object is to furnish a coating composition containing a poisonous substance, and which will solidify after its application to any suitable base, by which means scattering of the poison by 15 insects is avoided.

A further object is to provide a structure to which the coating is applied, such structure being shaped to be stacked in bundles for transportation or storage without deterioration of the composition.

A still further object is to supply a coating composition which will be attractive to lungless insects, practically harmless to children and domestic animals, and which after application, will be smooth and non-tacky.

With the foregoing objects outlined and with other objects in view which will appear as the description proceeds, the invention consists in the novel features hereinafter described in detail, illustrated in the accompanying drawing and more particularly pointed out in the appended claims.

In the drawing:

Fig. 1 is a perspective view of the card in accordance with the invention.

Fig. 2 is a sectional view of the same taken on the line 2—2 of Fig. 1.

In accordance with the invention I propose a liquid exterminator which can be applied to a rectangular cardboard card or the like, and which comprises the following ingredients.

(1) A mixture composed of the following:

- a. One-half gallon of water;
- b. One quart of ordinary mucilage or glue;
- c. One quart of glycerin; and
- d. One pound of lampblack.

These ingredients are first thoroughly mixed.

(2) A one gallon mixture of sorghum and simple syrup at a ratio of 1:3, respectively.

(3) Eight ounces of dissolved yellow phosphorus which is mixed with enough carbon disulphide to dissolve it.

(4) One pound of dextrin.

In mixing the ingredients of the composition, No. 1 mixture is first admixed with No. 2. After Nos. 1 and 2 have been thoroughly mixed, No. 4 is stirred in, and finally the dissolved phosphorus

is added and mixed with the rest of the ingredients. This composition provides a two-gallon mixture, capable of being applied to a card or other suitable base, and when it becomes dry, it adheres to the card or the like and forms a 5 smooth non-sticky coating thereon. The mixture can be applied to glass, wood, or any other suitable base as it is similar in fluid characteristics to ordinary coating compositions.

As shown in the drawing, a suitable card 1 of 10 cardboard or the like is partially covered on both sides with the composition as indicated at 2 and 3. This may be accomplished by dipping one end portion of the card into the mixture, so that only a portion of the card will be coated 15 and the remaining portion may be used as a handle in handling the card. Obviously this will permit such cards to be handled without the fingers coming into contact with the coating. Furthermore the blank space on the card may be 20 employed for advertising data or for directions, which may be printed thereon.

If the composition is applied to cards, such cards may be wrapped in Cellophane to preserve the composition until it is desired to use the card.

Instead of using black in the No. 1 mixture, it is obvious that any other coloring may be employed, but I have found that insects such as cockroaches and water bugs are attracted particularly by the black color.

It is also obvious that I may employ equivalents of the ingredients listed, and of course, may mix the ingredients in various ways without adhering strictly to the method outlined herein, although I prefer to employ such method as it has been found efficient in actual practice.

What I claim and desire to secure by Letters Patent is:

1. An insect exterminator consisting of a thin, stiff sheet-like member having a large area of 40 the front and back thereof completely coated with a non-tacky composition comprising a colored insecticide having as constituents thereof insect food and yellow phosphorus, the uncoated portion of said member forming a handle to facilitate 45 placement of the exterminator.

2. An insect exterminator consisting of a thin, stiff sheet-like member having a large area of the front and back thereof, its opposite edges and one adjacent end, completely coated with a non-tacky 50 composition comprising a colored insecticide having as constituents thereof insect food and yellow phosphorus, the uncoated portion of said member forming a handle to facilitate placement of the exterminator.
